Primary Examiner — Patricia Palasik*(74) Attorney, Agent, or Firm* — Lyman Moulton, Esq.(57) **CLAIM**

The ornamental design for a lathe tool height setting gauge, as shown and described.

DESCRIPTION

FIG. 1 is a top perspective view of a lathe tool height setting gauge showing my new design;

FIG. 2 is a front elevational view thereof;

FIG. 3 is a back elevational view thereof;

FIG. 4 is a top elevational view thereof;

FIG. 5 is a bottom elevational view thereof;

FIG. 6 is a left elevational view thereof; and,

FIG. 7 is a right elevational view thereof.

The broken lines in the drawings depict unclaimed environmental subject matter.
